William H. Morris

By Clarence A. O'Brien
Attorney

UNITED STATES PATENT OFFICE.

WILLIAM H. MORRIS, OF MARSHALLTOWN, IOWA.

DOOR HOLDER.

Application filed June 30, 1928. Serial No. 289,367.

The present invention relates to improvements in door holders or stops by which a door may be held in an open or partly open position; and it consists in certain novel features and combinations of parts aiming to improve upon such structures as are disclosed in Letters Patent 693,567 issued February 18, 1902 to Rosentreter.

Another very important object of the invention resides in the provision of a door holder of this nature which is exceedingly simple in its construction, easy to manipulate, strong and durable, inexpensive to manufacture, and thoroughly efficient and reliable in use and operation.

With the above and numerous other objects in view as will appear as the description proceeds, the invention resides in certain novel features of construction, and in the combination and arrangement of parts as will be hereinafter more fully described and claimed.

In the drawing:

Figure 1 is a side elevation of the door holder on the lower portion of a door,

Figure 2 is a perspective view of the plate, Figure 3 is a rear end elevation,

Figure 4 is a perspective view of the lever, and

Figure 5 is a perspective view of the rod.

Referring to the drawing in detail it will be seen that the numeral 10 designates the face plate which is fastened to the door and of elongated outline. The plate 10 has at a substantially central portion near its lower portion a hub 11 to receive pivot pins 12 for the lever 13 and at one side of said hub 11 said plate 10 is formed with the horizontal laterally projecting edge flange 14 while at the other side of said hub 11 the lower edge of said plate is recessed as is indicated at 15.

The plate 10 is substantially coextensive in length with the lever 13, which is substantially horizontal in its inoperative position, and said plate 10 above the shank end of the lever 13 extends upwardly as at 16 to a greater extent above the tag end of said lever. The lever 13 is in the form of a frame comprising a top 17 and a front or outer side 18, and said lever is formed at one end with a socket 19 and about its center with a horizontal hub 20, the latter extending inwardly from the front side 18 to the hub 11, formed on the base plate 10.

A pivot pin 12 extends through the front

side 18, hub 20, and hub 11 that may be headed on both ends. The socket 19 receives the upper end of the rubber or other plug or tag 21 which is securely held within the socket 19 by means of a screw 22 passing through an aperture in top of the lever 13 and entering 60 said tag.

The lower end of the tag 21 extends downwardly below the lever 13 and at the proper time will bind against the floor to hold the door open. The lever 13 is provided at one 65 side of the hub 20 with a rigid pin 23, whose ends are respectively held in the front 18 of said lever and a hanger 24 integral with and extending downwardly from the rear or inner edge of the top 17 of said lever.

The plate 10 adjacent the shank end of the lever 13 is provided with a rigid fulcrum horizontal plate 25 which extends outwardly from the plate 10 above the flange 14 and forwardly from a substantially vertical flange 40 at 75 the end of the flange 14 remote from the hub 11 and extends toward the hub 11. A rod 27 has a notch 28 at one end to receive the pin 23 and is bifurcated as at 29 at the other end which bifurcation tapers inwardly for receiving the edge of the fulcrum plate 25.

A flange 30 is formed on the rod 27 adjacent the notched end 28. A spring 31 of the coil type is disposed about the rod 27 and impinges against the plate 25 and against the flange 30. During the employment of the holder the rod 27 is adapted to have a pivotal action on the pin 23 and plate 25 from the position in which said rod is illustrated in dotted lines in Figure 1 to the inclined position in which said rod is indicated in full lines in Figure 1 and then back to its horizontal position.

The spring 31 is in a state of compression both when the lever 13 is in its horizontal or 95 inoperative position as well as when said lever is in its operative position and when the lever 13 is in its operative position the spring 31 operates by its expansive force to bind the tabs 31 in engagement with the floor.

Should the pad come over a depression in the floor the lever 13 is limited to the downward movement to cause the bifurcation 29 to limit the movement of the rod 27 and thus the parts are prevented from coming apart. 105 In the employment of the holder, the base plate 10, being fastened to the door, the lever 13 will be allowed to remain in its inoper-

tive position, except when it is desired to hold the door open or partly open position, and at such time the attendant will press his foot upon the pad end of the lever 13 until the 5 pin 23 has the tab above the horizontal central plane of the pivot pin 12 and at such time the expansive force of the spring 13 will drive the tab 21 against the floor and, binding the tab against the floor will hold 10 the door in its open or partly open position.

When it is desired to release the door, as for the purpose of closing the same, the attendant will press with his foot upon the shank end of the lever 13 until by the driving downward of the said end of the lever, the pin 23 has passed into line with or below 15 the central horizontal plane of the pivot pin 12, under which condition the expansive force of the spring 31 will operate to hold 20 the lever 13 in operative position.

Having thus described my invention, what I claim as new is:

1. In a door holder, a base plate fastened to a door, a lever pivotally secured at a 25 point intermediate its ends to said base plate and being normally horizontally disposed in a line with said base plate, a pin projecting from said base plate, a plate projecting from said base plate in spaced relation to said pin, a rod notched at one end to receive the pin 30 and bifurcated at its opposite end for reception of the last mentioned plate, said bifurcation being sufficiently long so that the rod

may slide on said last mentioned plate, and a coil spring on the rod and compressed between the last mentioned plate and a flange 35 on the rod and adapted to operate by its expansive force to bind said lever in its respective positions, and a pad on one end of the lever remote from said last mentioned 40 plate.

2. In a door holder, a base plate fastened to a door, a lever pivotally secured at a point intermediate its ends to said base plate and being normally horizontally disposed in a 45 line with said base plate, a pin projecting from said base plate, a plate projecting from said base plate in spaced relation to said pin, a rod having a notched end to receive the pin and being bifurcated at its opposite end 50 for reception of the last mentioned plate, said bifurcation being sufficiently long so that the rod may slide on said last mentioned plate, and a coil spring on the rod and compressed between the last mentioned plate and 55 a flange on the rod and adapted to operate by its expansive force to bind said lever in its respective position, and a pad on one end of the lever remote from said last mentioned plate, a flange projecting from the base plate 60 and adjacent the second mentioned plate and functioning as a stop for the downward movement of the adjacent end of the lever.

In testimony whereof I affix my signature.

WILLIAM H. MORRIS.
